(57) **CLAIM**

The ornamental design for a bug zapper, as shown and described.

DESCRIPTION

FIG. 1 is a front perspective view of an ornamental design for a bug zapper showing my new design.

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures are for environmental purposes only and form no part of the claimed design.

Any shading and cross-hatching are not features of the design but are utilized to illustrate the surface contours of the bug zapper in the drawings.
